(57) **CLAIM**

The ornamental design for a voltage regulator of AC generator for vehicle, as shown and described.

DESCRIPTION

FIG. 1 is a perspective view of the front, right, and top side of a voltage regulator of AC generator for vehicle showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken line portion of the figure drawings is included to show unclaimed subject matter only and forms no part of the claimed design.
